UNITED STATES PATENT OFFICE.

FREDERICK A. BRADLEY, OF NEW HAVEN, CONNECTICUT.

WHIP-SOCKET.

SPECIFICATION forming part of Letters Patent No. 292,977, dated February 5, 1884.

Application filed November 26, 1883. (No model.)

To all whom it may concern:

Be it known that I, FREDK. A. BRADLEY, of New Haven, in the county of New Haven and State of Connecticut, have invented a new Improvement in Whip-Sockets; and I do hereby declare the following, when taken in connection with accompanying drawings and the letters of reference marked thereon, to be a full, clear, and exact description of the same, and 10 which said drawings constitute part of this specification, and represent, in—

Figure 1, a front view; Fig. 2, a vertical central section; Fig. 3, a modification.

This invention relates to an improvement 15 in whip-sockets, with special reference to their attachment to carriages. Sockets have usually been attached, in the better class of carriages, to lugs made on the dash-frame; but objections have been made on account of 20 the time and trouble to fit the leather around the lugs, and also because of the difficulty to secure the sockets firmly.

The object of my invention is to overcome 25 these difficulties, and make a socket which can be readily attached to any carriage without connection with the dash-frame; and, it consists in the construction of the socket firmly united to a metal base, and secured to the carriage by a single bolt passing vertically 30 through the bottom of the socket and holder, which bolt serves as a means for securing the socket, as more fully hereinafter described.

A represents a common wooden socket; B, the cup-shaped holder or base into which the 35 socket is placed, and C the bolt through the bottom of the socket and holder.

I make the interior diameter of the cup part 40 of the holder B a very little less than the diameter of the socket A, so that considerable pressure will be required to force the socket into the holder. Before forcing the socket into the holder, I line the interior of the cup with white lead, or any equivalent substance, so that, when the socket is forced into the cup,

they become substantially one and the same 45 piece. After the parts have been thus united, a bolt, C, is passed vertically through the bottom of the socket and base, and screw-threaded on its lower end, to receive a nut, E.

To secure the socket to the carriage, simply 50 make a hole for the bolt—say in the rocker D, or at the point it is desired to be secured; then pass the bolt through the hole, and apply the nut, as shown in Fig. 2. The head of the bolt, taking its bearing upon the bottom of the 55 socket, draws the socket and base so firmly together that the lining of the white lead in the cup may be dispensed with, and the interior diameter of the cup made the same or greater than the diameter of the socket.

I preferably make the holder B a malleable 60 iron, it being cast with the hole through the center for the bolt to pass.

In order to allow the water which may fall into the socket to pass off, I make perforations 65 f around the bottom of the socket, as seen in Fig. 2; or it may be accomplished by using a hollow bolt, g, as seen in Fig. 3.

In case it should be desired to secure the socket from a point at right angles to the socket, 70 instead of directly below it, the securing devices may be made fast to or made a part of the socket, extending radially from the socket. It that case the bolt will be shortened, so that the end will bear directly against the bottom 75 of the base, and thus bind the socket firmly to the base.

I claim—

The combination of the socket A, the metal base B, constructed to receive the lower end 80 of the socket, and the bolt C through the bottom of the socket and base, whereby the base and socket are secured together, substantially as and for the purpose described.

FREDERICK A. BRADLEY.
